Primary Examiner — Sheryl Lane*Assistant Examiner* — Nicole C Shiflet*(74) Attorney, Agent, or Firm* — Birch, Stewart, Kolasch & Birch, LLP(57) **CLAIM**

The ornamental design for an electric oven range, as shown and described.

DESCRIPTION

1. Electric oven range
1.1 is a perspective view of an electric oven range, showing our new design;
1.2 is a front elevation view thereof;
1.3 is a rear elevation view thereof;
1.4 is a left-side elevation view thereof;
1.5 is a right-side elevation view thereof;
1.6 is a top plan view thereof;
1.7 is a bottom plan view thereof; and
1.8 is a front perspective view thereof showing the buttons in a pressed position.
The broken lines showing portions of the article form no part of the claimed design.

1 Claim, 8 Drawing Sheets(56)
